Primary Examiner — Wan Laymon(74) *Attorney, Agent, or Firm* — Hansen IP Law PLLC**CLAIM**

The ornamental design for a hat, as shown and described.

DESCRIPTION

The single view is a front elevational view of a hat showing our new design.

The broken lines surrounding the outline of the electrical outlet logo in the figure are for purposes of illustrating environmental structure and form no part of the claimed design. The broken lines defining the three plug receptacles in the interior of the electrical outlet logo form no part of the claimed design.
